UNITED STATES PATENT OFFICE

LADISLAV BALGA, OF POUGHKEEPSIE, NEW YORK

RAZOR BLADE SHARPENER

Application filed November 4, 1930. Serial No. 493,408.

This invention relates to improvements in razor blade sharpeners and comprises a U-shaped frame having secured to the base thereof a clamping device whereby the same 5 may be clamped to a temporary support and the U-shaped frame is adapted to support a pair of rollers at opposite ends thereof, one of said pairs of rollers being adjustable relative to the other pair whereby the endless 10 belt or strop passing over opposite pairs of rollers may be adjusted. The invention also comprises means for turning one of the rollers comprising a hand crank mounted on a shaft having a suitable gear meshing with a 15 corresponding gear on the shaft of one of the rollers whereby one of the strops will be moved and the roller at the opposite end of the strop will be rotated and said rotation may be communicated to the other strop by 20 means of the intermeshing gears associated with the shaft of each of the rollers carried by the adjustable frame member.

It is also a purpose of this invention to 25 provide a device of the above mentioned character with a novel form of blade holder adapted to be positioned relative to the U-shaped frame, whereby the razor blade may be presented to the alternate surfaces of the endless stropping belt.

30 A further object of this invention, is to provide removable shafts for the rollers and means for holding the rollers in place relative to the U-shaped frame and the adjustable frame movable thereto.

35 A still further object of this invention, is to provide a device of the above mentioned character, adapted to be easily manufactured and constructed and having comparatively few parts to become out of order and worn.

40 Other objects and advantages of the invention, will become apparent during the course of the following description, forming a part of the specification and in which,

45 Figure 1 is a side elevation of the invention, illustrating the U-shaped frame clamped to a temporary support and illustrating the movement by way of dotted lines of the razor blade holder;

50 Figure 2 is a top elevation illustrating the general contour of the frame and showing the

adjustable roll supporting frame at one end thereof;

Figure 3 is a front elevation illustrating the manual drive connection between the crank arm or handle and one of the supporting rolls; 55

Figure 4 is a rear elevation of the device illustrating the general configuration of the U-shaped frame and the adjustable roll supporting head at one end of the frame; 60

Figure 5 is a longitudinal cross-sectional view taken on line 5—5 of Figure 1 illustrating the manner in which the adjustable frame and endless strop supporting roll are positioned relative to the U-shaped frame and the blade holder is illustrated in dotted lines to show the position thereof relative to the endless stropping belt; 65

Figure 6 is a longitudinal cross-sectional view taken on line 6—6, looking in the direction of the arrows in Figure 1, illustrating the endless strop rolls and the manner in which the same are retained relative to the U-shaped frame and the adjustable end frame; 70

Figure 7 is a vertical cross-sectional view taken on line 7—7 of Figure 1, looking in the direction of the arrows and illustrating further the endless strop supporting rolls and the intermeshing gearing between one of the 80 rolls and the crank arm;

Figure 8 is a vertical cross-sectional view taken on line 8—8 of Figure 1, looking in the direction of the arrows illustrating the adjustable frame in cross section and showing 85 the endless strop supporting rolls rotatably carried upon supporting pins;

Figure 9 is a perspective view of the U-shaped frame illustrating the stopping belt as associated with the supporting rollers; 90

Figure 10 is a vertical elevation of the razor blade holder showing the same partly broken away to illustrate the manner in which the cross levers may be held in their locked or closed position; 95

Figure 11 is a side elevation of the razor blade holder illustrating in dotted lines the manner in which the pivoted cross-levers may be separated for positioning the blade between the jaws and illustrating the locking 100

device partly in section to show the manner in which the end of one of the cross-levers is locked against displacement; and

Figure 12 is a transverse cross-sectional view taken on line 12—12 of Figure 10 illustrating the cross levers in cross-section and showing the fulcrum formed integral with one of the levers.

In the drawings, wherein for the purpose of illustrating the invention and wherein like reference characters will be employed to designate like parts throughout the same, the reference character 1 will generally be employed to designate a U-shaped frame having vertical sections 2 and 3 extending upwardly from the base portion. Secured to the base of the U-shaped frame 1 is a U-shaped clamping device 4 having one leg as at 5 secured to the underportion of the U-shaped frame 1 by welding or the like. The opposite leg 6 of the U-shaped clamp 4 is provided with a screw threaded opening 7 adapted to receive corresponding screw threads on a screw threaded bolt or clamping device 8. On one end of the screw threaded bolt 8 is provided a disk 9 while the opposite end is provided with a handle 10 to accommodate turning movement of the screw threaded bolt 8, whereby the disk 9 may be moved into engagement with the underside of a temporary support T for supporting the U-shaped frame 1 thereon.

Formed integral with an extending laterally from the vertical portions 2 and 3 of the U-shaped frame 1 are a pair of supporting extensions 11 and 12 which taper together at their free ends as clearly illustrated in Figure 1.

Mounted between the vertical portions 2 and 3 of the U-shaped frame member 1 are a pair of roller supporting pins 13 and 14 which are mounted for rotary movement and for supporting rolls 15 and 16 adapted to be rigidly held thereon by means of pins 17 and 18. Each of the rollers 15 and 16 may be provided with angular bores 19 for furnishing a lubricant to the pins 13 and 14 whereby the journals thereof in the vertical frame members 2 and 3 may be lubricated.

The uppermost roller pin 13 is extended as at 20 for receiving a small gear wheel 21 which is adapted to be held thereon in a rigid fashion and which is adapted to mesh with a gear wheel 22 having corresponding end projections 22 and 23 forming bearings for the gear wheel in an extension 24 and the vertical U-shaped frame portion 3 and a member 25 having an angular portion 26 adapted to be secured to the vertical extension 3 of the U-shaped frame by means of a screw 27. The upper end of the member 25 is bent as at 28 to form a leg or supporting portion 29 terminating in an angular portion 30 adapted to be secured to the upper portion of the vertical U-shaped frame member 2 by means of a

screw 31. A crank arm 32 may be rigidly secured to the extension 23 and a handle 33 may be secured to the crank arm 32 by means of a crank pin 34.

The roller supporting pins 13 and 14 may be held in place relative to the vertical arms 2 and 3 of the U-shaped frame 1, by means of spring clips 35 presented over the ends of the pins 13 and 14 and held to the U-shaped frame member by a screw or the like 36.

Associated with the free ends of the lateral frame extensions 11 and 12 is a slideable roll supporting member 37 having extending angularly thereto on each side thereof a pair of roll holding arms 38 and 39. Rotatably mounted within the pair of roll holding arms 38 is a roll supporting pin 40 to which is rigidly secured an endless stop belt roll 41 by means of a transverse pin 42 passing therethrough and through the pin or bearing 40.

The pin 40 extends through a slot 43 in each of the roll supporting arms 38 to allow lateral movement of the roll 41 and the roll supporting member 37. The spring fingers 44 may be secured to the roll holding arms 38 by means of rivets or screws 45 whereby the free ends of the spring fingers 44 will be presented to the ends of the pin 40. Secured to one end of the roll 40 as by means of screws 46 is a gear wheel 47 which extends beyond the periphery of the roll 41 and is adapted to engage a similar gear wheel 48 on a roll supporting pin 49 having its ends journaled in the lower roll supporting arms 39. Rigidly secured to the pin 49 is a strop supporting roll 50 which is held in a rigid manner by means of a transverse pin 51 similar to the transverse pin 42. A spring clip 52 is secured by means of a rivet or screw 53 to the lower roll supporting arms 39 and the free end of the spring finger 52 is presented to the ends of the roll supporting pin 49 in a manner similar to the spring fingers 44 for holding the roll supporting pin 40 in place.

The free ends of the laterally extending frame members 11 and 12 are connected by side pieces 54 and angularly extending lugs 55 are formed on the lateral and vertical edges of the side pieces 54 whereby the same may be engaged by thumb screws 56 having knurled thumb pieces 57 for turning the screw threaded members 56 through threaded openings in the roll supporting member 37. A knurled locking nut 59 is threaded on the knurled screws 56 to lock the screws in an adjusted position and hold the strop supporting rolls 41 and 50 in an adjusted relation to the frame members 11 and 12. It is to be noted that the roll supporting pin 49 is adapted for longitudinal sliding movement in slots 60 formed in the ends of the laterally extending frame members 12 whereby the roll supporting member 37 and rolls 41 and 50 may be moved longitudinally relative to the frame members

115
120
125
130

11 and 12 by turning movement of the knurled screws 57.

An endless leather stropping belt 61 is adapted to pass over the rolls 15 and 41 while a similar leather stropping belt 62 is adapted to pass over the lower supporting rolls 16 and 50 and it will be noted that the portions of the endless belt adjacent the rolls 41 and 50 are closer together than at the points adjacent the rolls 15 and 16.

10 The blade holder comprises a pair of crossed handles 64 and 65 pivotally secured together as at 66 and the pivoted handle 65 terminates in a blade holding jaw 67 while the handle member 64 terminates in a blade holding jaw 68. Formed on the end of the crossed handle 64 is a boss 69 adapted to slidably receive a cylindrical locking device 70 which is provided with a bearing portion 71 adapted to closely engage the boss 69 and guide the cylindrical portion thereof as at 72 over the handle 64. A coil spring 73 has one of its ends bearing against the guide portion 71 of the cylindrical member 70 while the opposite end of the coil spring impinges against a washer 74 held in place by a screw 75 entering the end of the boss 69. The locking cylindrical member 70 may be manipulated in order to allow the cylindrical portion 72 to confine the ends of the cross handles 64 and 65 in the position shown in Figures 10 and 11 whereby the jaws 67 and 68 will be held in close contact with each other. Formed integral with the cross handle 64 are

25 a pair of oppositely extending angular members 77 which extend forwardly as at 78 and terminate in angular portions 79 adapted to be received in notches 80 in the lateral edges of the vertical U-shaped members 2 and 3, whereby the blade holder may be positioned between the rolls 15 and 16 as illustrated in Figure 1.

For a consideration of the operation of the invention, attention is directed to Figure 1, wherein is illustrated the U-shaped frame 1 secured to a temporary support T. By inserting the blade to be sharpened between the jaws 67 and 68 of the blade holder and clamping the cross handles 64 and 65 in a locked position by means of the locking sleeve 70, the blade may be presented between the endless stropping belts 61 and 62 in such a manner that the angular portions 79 formed on the cross handle 64 may be received in the notches 80 formed in the lateral edges of the vertical members 2 and 3 of the U-shaped frame 1. In this manner, the blade may be alternately moved into engagement with the endless stropping belt in Figure 1 and by turning movement of the crank arm 32 and handle 33, the same may be caused to rotate by means of the gear 22 meshing with the gear 21 on the roll 15 which imparts motion to the roll 41 by means of the endless stropping belt 61 in a counterclockwise direction, which

motion is transmitted to the endless stropping belt 62 by means of gears 47 and 48 on the stropping belt supporting rolls 41 and 50, whereby the lower stropping belt 62 may be caused to rotate or move in a clockwise direction. As for instance, the continuous complementary faces of the endless stropping belts 61 and 62 will move away from the U-shaped frame 1 and in the direction of the lateral extensions thereof 11 and 12, whereby the blade B held between the jaws 68 and 67 of the blade holder may be sharpened and provided with an edge by moving the cross-handles 64 and 65 in the positions illustrated in dotted lines in Figure 1.

When it is desired to adjust the endless strop 61, to tighten or loosen the same upon the rolls 15, 40, 16 and 50, the locking thumb pieces 59 are loosened upon the screw threaded thumb nut 56 to allow the thumb nut 57 to be turned and move the roll supporting member 37 relative to the laterally extending frame members 11 and 12.

It is to be understood, that the bores 19 in the rolls 15 and 16 are similar to the bores 90 in the rolls 41 and 50 and that a lubricant may be admitted thereto for reducing the friction of the journals of the pins 40 and 49.

It is also to be understood that the form 95 of the invention herewith shown and described is to be taken as a preferred embodiment of the invention and that various changes in the shape, size and arrangement of parts may be resorted to without departing from the spirit of the invention or the scope of the subjoined claims.

I claim:—

1. A razor blade sharpener of the character described, comprising a U-shaped frame, a clamp associated with the base section of the U-shaped frame, whereby the same may be detachably secured to a temporary support, a pair of endless belt supporting rolls mounted between the vertical sections of the U-shaped frame for rotary movement therebetween, a vertical extension carried by one of the vertical sections of the U-shaped frame, a crank shaft passing through the vertical extension and being rotatably mounted 105 therein, a handle mounted on the opposite end of the crank shaft, a gear mounted on the crank shaft between the vertical extensions and the vertical section of the U-shaped frame, a gear wheel mounted in a rigid fashion on one of the rolls supported between the vertical sections of the U-shaped frame, adapted to engage the above mentioned gear wheel, a pair of lateral extensions formed on each of the vertical sections of the U- 110 shaped frame, a U-shaped sliding cross-head mounted on the free ends of the lateral U-shaped frame extensions, means associated with the U-shaped cross-head for moving the same relative to the lateral extensions, a 115

pair of endless belt supporting rolls carried by the adjustable U-shaped cross-head, an endless stropping belt passing over one of each of the pairs of endless belt supporting rollers whereby the complementary continuous moving faces may move in the same direction, means for presenting a razor blade between the complementary moving faces of the endless belt, said means including a pair of cross-levers having jaws on one end thereof, a cross-member carried by one of the levers, said cross-member being adapted to be received in notches in the vertical sections of the U-shaped frame, a locking device carried by the end of one of the cross-handles, and means for holding the locking device into engagement with the ends of both of the cross-handles whereby the blade held between the jaws will be locked in position and against movement.

2. A safety razor blade sharpener of the character described, comprising a U-shaped frame, a clamping device associated with the base portion of the U-shaped frame whereby the same may be detachably secured to a movable support, a pair of endless belt supporting rolls rotatably mounted between the vertical sections of the U-shaped frame, a pair of lateral extensions formed integral with each of the vertical sections of the U-shaped frame, a vertical extension secured to one of the vertical sections of the U-shaped frame, a shaft passing through the vertical extension and the free ends of one of the vertical sections of the U-shaped frame, the crank arm rigidly secured to the shaft, a handle secured to the opposite end of the shaft, whereby turning of the handle will cause a rotary motion to the shaft, a gear wheel mounted on the shaft in a rigid fashion between the vertical extension and a vertical section of the U-shaped frame, a gear wheel mounted on one of the rollers adapted to mesh with the above mentioned gear wheel, a U-shaped adjustable roll frame slidably mounted and carried by the free ends of the lateral extensions, a pair of endless belt supporting rolls rotatably mounted within the adjustable roll supporting frame, thumb screws passing through the adjustable roll supporting frame having their ends engaging flanged portions on the lateral extensions whereby turning movement of the thumb screws will cause sliding movement of the adjustable roll supporting frame, a gear wheel rigidly secured to each of the rolls, between the adjustable roll supporting frame, an endless stropping belt passing over one of each of the pairs of rollers above mentioned, the complementary continuous moving faces of the endless stropping belt being adapted to move in the same direction, and toward the adjustable U-shaped roll supporting frame, and a blade holder pivotally mounted between the vertical sections of the U-shaped frame whereby the

blade carried thereby may be alternately presented to the continuous moving faces of the endless stropping belts.

In testimony whereof I affix my signature.
